T. V. PLICE,
SWIVEL HANGER FOR DOORS,
APPLICATION FILED FEB. 12, 1920.

1,343,789.

Patented June 15, 1920.

UNITED STATES PATENT OFFICE.

THOMAS V. PLICE, OF ASHLAND, OHIO, ASSIGNOR TO THE TOPPING MANUFACTURING CO., OF ASHLAND, OHIO, A CORPORATION OF OHIO.

SWIVEL-HANGER FOR DOORS.

1,343,789.

Specification of Letters Patent. Patented June 15, 1920.

Application filed February 12, 1920. Serial No. 358,035.

To all whom it may concern:

Be it known that I, THOMAS V. PLICE, a citizen of the United States of America, residing at Ashland, Ohio, have invented 5 new and useful Improvements in Swivel-Hangers for Doors, of which the following is a specification.

My invention relates to improvements in door hangers and consists primarily in providing in connection therewith effective stop and hold-back mechanism which in the preferred form is adjustable and reversible.

In the accompanying drawings, I have shown my invention in its preferred form in 15 which—

Figure 1 is a front view of my invention as applied to a door.

Fig. 2 is a plan view partly in section showing the door closed.

20 Fig. 3 is a similar view showing the door open.

Fig. 4 is a front elevation relatively enlarged of the hanger and hold back.

25 Fig. 5 is an edge view of the parts shown in Fig. 4 looking from right to left.

Fig. 6 is a perspective view of certain details.

Fig. 7 is a side view of the door stop.

30 1—1 represent the top and sides of a door casing. 2—3 represent two doors. The door 2 is hinged to the door casing 1 so as to swing outwardly. The door section 3 is hinged to the door section 2 so as to swing inwardly relatively thereto (see Fig. 3).

35 4 is an overhead track from which the door section 3 is supported by means of a hanger attached to the upper free edge of said section. The hanger is provided with the usual anti-friction wheel arranged to ride along

40 on the track 4 so that the two doors will receive support from the track 4 through the medium of the hanger. The hanger is of the swivel type, that is to say, it comprises the wheel carrying frame 5 having a

45 swivel connection with a bracket 6, the bracket being suitably secured to the door by means of screws, bolts or otherwise. It follows that as the door sections are moved from the closed position, Fig. 1, to the open

50 position shown in Fig. 3, the doors will partake of a rotary movement relatively to the wheel carrying portion of the hanger. It also is apparent that if the end of the track is curved or offset as shown in Figs. 2 and

55 3, the wheel carrying frame of the hanger

will partake of a rotary movement relatively to the door. It is apparent that as the doors partake of this compound swinging and sliding movement, it is only with the greatest difficulty that a simple and effective stop and hold back mechanism may be employed in connection with said doors.

In my invention, instead of associating the hold back connection with the doors, I associate it with the track and hanger so that 60 no matter what may be the location of the stop itself, the hold back device will always be so positioned relatively to the stop that it may be interengaged therewith for the purpose of holding the door open. By looking at Fig. 3, it will be apparent that unless an effective hold back means is provided, a

65 draft of air creating pressure against the left hand side of the door section 2, would tend to move the doors into the closing position, which would endanger the safety of

70 a vehicle being backed out of a building equipped with such doors. Accordingly, to guard against this possible danger and injury, I have provided the hold back mechanism referred to and I have so constructed the same that it may be adjusted to any de-

75 sired position and may be reversed so as to be associated with doors opening either to the right or left. The stop, itself, com-

80 prises a C-shaped member 7 which is ar- ranged to slide on the track 4 and which may be locked in any position thereon by a set screw or bolt 8. Extending outwardly

85 from the member 7 is an offset shoulder or abutment 9 through which the set screw or bolt passes and which offset constitutes the stop, *per se*. When the stop is adjusted on the track 4 at the desired position and the door is opened, the edge of the wheel carry-

90 ing frame 5 will eventually strike said stop, as shown in Fig. 3, and stop the further opening of the door. On the upper and lower edges of the abutment 9 I form flanges

95 10—10. 11 is a latch, pivoted intermediate its length on a stud 12 carried by the wheel carrying frame 5. One end of this latch is provided with a beveled hooked nose 14, while the other end is provided with a short arm to which a chain 15 may be attached so

105 that by pulling down on the chain the hooked end of the latch may be lifted. 16—17 are stops on opposite sides of the wheel carry-

110 ing frame which limit the rocking movement of the latch in both directions. 18 is

a cotter pin which constitutes one convenient means of holding the latch on the stud 12. The hooked end of the latch is preferably weighted by making said hooked end 5 sufficiently bulky, as shown. This weighted end normally rests on the stop shoulder 16 so that the bevel side of the latch will, when the door is opened, engage the upper flange 10 of the stop and be lifted thereby so as to 10 drop back of the same in the manner shown in Fig. 6, thereby holding the door opened until manually released, thus preventing any accidental closing, or partial closing, of the door by drafts or otherwise. By mounting 15 the latch on the roller carrying frame, it is apparent that the latter will always serve to guide the latch directly to the stop so that it may be lifted thereby to engage therewith for hold back purposes. Manifestly, if 20 the hold back latch were carried by either of the door sections, special means would have to be provided to guarantee the proper inter-engagement of the same with any suitable abutment shoulder, and this would have 25 to be varied according to various positions of adjustment. In the present instance, it matters not where the door stop is placed upon the track, the latch will always be guided properly into inter-engagement there- 30 with by the wheel carrying frame 5. I provide a rib 10 on the upper and lower side of the stop so that this stop may be reversed in its position on the rail or track 4. It will also be noted that by removing 35 the cotter pin 10, the latch may be reversed on the wheel carrying frame 5 thus adapting my invention to either a right or a left hand door structure.

It will be seen from the foregoing that my 40 invention has particular utility in connection with door hangers in which one part of the track is offset from the door casing to a greater degree than another part. As shown in the drawings, that part of the 45 track which supports the hanger when the door is closed is relatively close to the door casing so that the door when closed will stand in the proper position. On the other hand, that part of the track which supports 50 the hanger when the door is open is offset from the door casing to a greater degree because it is obvious that the door hanger itself will tend to move away from the plane of the door casing as the doors are folded 55 back, the extreme outward movement occurring when it is desired to fold the doors back to an even greater degree than shown in the drawings, and for example, as far back as will cause said doors to lie substantially parallel with the plane of the casing. In this latter event the door hanger will stand away from the casing somewhat more than the sum of the thickness of the two 60 door sections. In such a construction, it is

obvious that there would be great difficulty 65 in providing effective stop mechanism were it not constructed in the substantially new manner shown herein which permits the stop and hold back shoulder to be located anywhere on the rail irrespective of the degree 70 of offset of that part of the rail where said stop is to be placed.

What I claim is:

1. In a door support of the type comprising a fixed supporting track and a door 75 hanger designed to ride thereon, a stop on said track, said door hanger comprising a bracket arranged to be secured to a door, a frame carrying a wheel designed to run on said track, a connection between said frame 80 and said bracket, a latch carried by the wheel carrying frame arranged to interlock with said stop on said track when the door to which the hanger is attached is open.

2. In a door support of the type comprising a fixed supporting track and a door 85 hanger designed to ride thereon, a stop on said track, said door hanger comprising a bracket arranged to be secured to a door, a frame carrying a wheel designed to run on 90 said track, a swivel connection between said frame and said bracket, a latch carried by the wheel carrying frame arranged to interlock with said stop on said track when the door to which the hanger is attached is open, 95 said stop being adjustable on said track, said latch being arranged to engage said stop in its various positions of adjustment.

3. In a door support of the type comprising a fixed supporting track and a door 100 hanger designed to ride thereon, a stop on said track, said door hanger comprising a bracket arranged to be secured to a door, a frame carrying a wheel designed to run on said track, a swivel connection between said 105 frame and said bracket, a latch carried by the wheel carrying frame arranged to interlock with said stop on said track when the door to which the hanger is attached is open, said latch being pivotally mounted on 110 said frame and reversible relative thereto.

4. In a door support of the type comprising a fixed supporting track and a door 115 hanger designed to ride thereon, a stop on said track, said door hanger comprising a bracket arranged to be secured to a door, a frame carrying a wheel designed to run on 120 said track, a swivel connection between said frame and said bracket, a latch carried by the wheel carrying frame arranged to interlock with said stop on said track when the door to which the hanger is attached is open, said stop being adjustable on said track, said latch being arranged to engage said stop in its various positions of adjustment, the 125 connection between said frame and bracket being in the form of a swivel.

THOMAS V. PLICE.
